UNITED STATES PATENT OFFICE.

PHILIBERT ALBERT MARIUS DUBIEF, OF COURBEVOIE, FRANCE.

APPARATUS FOR THE REPRODUCTION OF DRAWINGS BY ARTIFICIAL LIGHT.

1,425,636.

Specification of Letters Patent. Patented Aug. 15, 1922.

Application filed September 2, 1919. Serial No. 321,127.

To all whom it may concern:

Be it known that I, PHILIBERT ALBERT MARIUS DUBIEF, of 28bis Rue Armand Sylvestre, Courbevoie, Seine, France, have invented Improvements in Apparatus for the Reproduction of Drawings by Artificial Light, of which the following is a clear, full, and exact description.

This invention has for its object to provide improved apparatus for the reproduction of drawings by artificial light, allowing to provide an apparatus of strong, cheap and simple construction, in which the motor producing the displacement of the source of light occupies a small space and the running of which is regular, silent and adjustable at will.

According to this invention, the displacement of the source of light is obtained by the descent of a counterweight carried by a lower double pulley on which passes a cable which, passing round an upper double pulley loosely mounted on a fixed shaft, controls the displacement of the source of light; one end of this cable is attached to a fixed point and the other to the support of the source of light. A liquid brake is connected to the lower double pulley so as to permit of adjusting the speed of the descent of the counterweight and consequently, the speed of displacement of the source of light as well as that of the reproduction, according to the nature and sensitivity of the papers employed.

The apparatus constructed according to this invention may conveniently comprise, in any case, a cut out actuated by the counterweight at the end of its downward movement so as to automatically cut the current at the end of each reproducing operation.

In the accompanying drawings is shown, by way of example only, an apparatus for the displacement of the source of light applicable to apparatus for the reproduction of drawings by artificial light.

In these drawings:

Figure 1 is a longitudinal vertical section of an apparatus constructed in accordance with this invention;

Figure 2 is an end view;

Figure 3 shows diagrammatically in perspective the control and driving device for the source of light;

Figures 4 and 5 are detail views, on an enlarged scale, of the lamp-carrier; 55

Figure 4 is a vertical longitudinal section thereof on line A—A of Fig. 5;

Figure 5 is a plan view;

Figure 6 shows in vertical section the liquid brake; 60

Figure 7 is a side elevation of a modification of the device producing the displacement of the lamp and its application to an ordinary vertical frame.

As illustrated in Figures 1 to 5, the improved apparatus comprises a fixed glass cylinder *a* arranged in a horizontal or inclined position and supported in any suitable manner on a frame *b* for receiving the drawings to be reproduced. 65

Within this cylinder can be displaced longitudinally any suitable source of light which, in the example illustrated, is in the form of a metallic filament lamp *c* mounted on a special carriage *d*. 70

This carriage, made of insulating material and illustrated in Figures 4 and 5, is carried by two fixed conducting rods *e*, *f* on which it is guided by eyes formed by two contact blades *g*, *h* constituted by brushes and secured to this support, as clearly shown in Fig. 4, the said blades coming respectively in contact with a metallic member *g'*, fitting against the cap of the lamp, and with the contact *c'* of the lamp. 85

The carriage *d* may be moved longitudinally in a certain direction within the cylinder *a* and is connected, for that purpose, to a cable or chain *i* which passes under the pulleys *j* and *k* and the free ends of which are attached at *i'* and *i''* to the carriage *d*. 90

The pulley *k* carries a driving crank *m* by means of which the carriage *d* may be brought back to its starting position for obtaining a proof.

The longitudinal displacement of the lamp-carrying carriage in the reverse direction is automatically obtained by the descent of the counterweight *l*.

This counterweight *l* is carried, for that purpose, by a rod *n* serving as an axis of rotation for a double pulley *o* suspended to a cable *p* passing round this pulley and another double pulley *q* loosely mounted on the shaft *j'* of the pulley *j*, the ends of this cable *p* being respectively attached to a 100

fixed point r of the frame b and to the carriage d of the lamp c .

The speed of descent of the counterweight l may be adjusted at will by means of a liquid brake or regulator fully shown in Fig. 6.

The rod s of the piston of this regulating device is carried by a fork piece s^1 on the axis of the lower double pulley o carrying the counterweight l , so that the piston t follows the vertical movements of the said counterweight l .

This piston t is enclosed in a cylinder u secured in any suitable manner to the frame 15 of the apparatus and filled with a suitable liquid, such as oil for instance.

The head of the piston t is perforated with opening t^1 which may be more or less uncovered by a sleeve v , also perforated and 20 surrounding the head of the piston t , the said sleeve being prolonged, for that purpose, outside the fixed cylinder u by a socket v^1 surrounding the rod of the piston and provided with a driving handle v^2 .

It will be understood that by turning this handle in one direction or the other, the cross sectional area of the openings t^1 of the piston t is varied and it is thus possible to adjust at will the descent of the piston 30 and the fall of the counterweight, so as to modify the speed of displacement of the lamp c according to the nature and sensitivity of the papers used for the reproduction.

The operation of this apparatus is as follows:

A motion of rotation is imparted to the shaft j^1 carrying the upper double pulley q by rotating by hand the crank m of the 40 pulley k .

This action has for its result, on the one hand, (through actuation of the cable i) to bring the lamp to the right-hand end of the cylinder a on which are arranged in the 45 ordinary manner the drawings to be reproduced and, on the other hand, to raise, through the traction exerted by the carriage d on the cable p , the actuating counterweight l and the piston t of the brake to 50 their upper or raised position, in which the lamp c is automatically lighted by reason of the closing of the lever switch x .

The cross sectional area of the openings t^1 in the piston of the liquid regulator being 55 suitably adjusted by the manipulation of the handle v^2 , it is then simply necessary to remove the hand from the crank m .

Under the action of gravity, the counterweight descends, producing at the same time 60 the unwinding of the cable p passing on the pulleys o and q and attached, as above mentioned, to the fixed point r and to the carriage d carrying the lamp c .

By means of this arrangement, as clearly 65 shown in Fig. 3, the traction exerted on the

cable p by the descent of the counterweight l produces the displacement of the lamp-carrying carriage d towards the left of the cylinder a .

The lamp is therefore moved automatically 70 and longitudinally within the cylinder a up to the left-hand end of the latter, the movement of the counterweight being adjusted in such a manner that, when the lamp is at the end of its movement, the counterweight 75 determines the opening of the switch x which, as shown in Fig. 3, cuts the feeding of the current to the lamp.

Figure 7 illustrates a modified arrangement enabling one to use the above described 80 driving apparatus with vertical plane frames.

In this application, the driving device still comprises a counterweight l , carried by a lower double pulley o , on which passes a 85 cable p surrounding a fixed upper double pulley q .

The ends of the said cable are attached, on one side, to a fixed point r and, on the other side, to the lamp-carrier d^1 provided 90 with a reflector d^2 and suitably guided on vertical rods j .

The whole of the apparatus, including the oil regulator and the switch, is carried by a vertical standard z secured on a support or base of suitable shape.

The operation of this apparatus is exactly the same as that previously described, except that the lamp moves vertically opposite the ordinary plane frame z^1 .

It is to be understood that the driving device of the source of light described above is given only by way of example and it is obvious that the shape, materials, sizes and detail arrangements may be varied without 105 departing from the scope of the invention.

Claims—

1. An apparatus for the reproduction of drawings by artificial light, comprising in combination, a frame; an electric lamp; a 110 movable carriage for the lamp; fixed conducting guide rods for and insulated from the carriage; contact members connecting the lamp to the said guide rods; a driving counterweight; a plurality of pulleys; a cable 115 passing over the pulleys and attached to the frame and to the carriage for moving the lamp in one direction; a hydraulic brake for retarding the descent of the counterweight and controlling the speed of the 120 lamp; means for lighting and extinguishing the lamp; and means, adjacent to the movable carriage and lamp, for receiving and holding the drawings.

2. An apparatus for the reproduction of 125 drawings by artificial light, comprising in combination a frame; a fixed cylinder, mounted on the frame, for receiving and holding the drawings; an electric lamp within the cylinder; a movable carriage for 130

the lamp; fixed conducting guide rods for and insulated from the carriage; contact members connecting the lamp to the said guide rods; a driving counterweight; a plurality of pulleys; a cable, passing over the said pulleys and attached to the frame and to the carriage for displacing the lamp longitudinally in the cylinder in one direction; means for moving the lamp carriage by hand 10 in the other direction, a hydraulic brake

for retarding the descent of the counterweight and controlling the speed of the lamp, and means for lighting and extinguishing the said lamp.

The foregoing specification of my improvements in apparatus for the reproduction of drawings by artificial light, signed by me this 23rd day of July, 1919. 15

PHILIBERT ALBERT MARIUS DUBIEF.
